UNITED STATES PATENT OFFICE.

LOUIS C. BELZ AND ARNOLD NACKE, OF PHILADELPHIA, PENNSYLVANIA, ASSIGNEES
TO THE TRI-PRONG HAIR PIN CO., A CORPORATION OF NEW JERSEY.

WIRE-DRAWING DIE.

1,163,062.

Specification of Letters Patent.

Patented Dec. 7, 1915.

Application filed March 24, 1914. Serial No. 826,875.

To all whom it may concern:

Be it known that we, LOUIS C. BELZ and ARNOLD NACKE, citizens of the United States, and residents of Philadelphia, county of Philadelphia, and State of Pennsylvania, have invented an Improvement in Wire-Drawing Dies, of which the following is a specification.

Our invention has reference to wire drawing dies adapted for use, among other purposes, in making drawn wire suitable for making tri-prong hair pins of the construction set forth in Letters Patent No. 1,026,142, granted May 14, 1912, and for use in the method of drawing wire therefor set out in application Serial No. 755,059, filed on March 17, 1913, by Louis C. Belz, one of the present applicants. It will be understood that the said dies are also suitable for drawing wheel spokes or for other purposes where two or more diameters or cross sectional areas are required in a given length.

The object of our invention is to provide a two-part wire drawing die for making articles of wire which have a portion of their length reduced in diameter so that the completed article is formed of a wire having lengths of different cross sectional areas, and which die is so designed and constructed as to automatically remove the fin or fins formed during the initial pinching action of the dies whereby the material leaves the die in a substantially finished condition and without fins or rough edges usually formed by the action of a drawing die.

It has for a further object to provide a means for limiting the clamping action of the dies so that the cutting devices for severing the fins or rough edges are protected from damage during the operation of the die.

Our invention consists of a two-part drawing die having the throat portions provided with cutting edges which during the initial reduction of the wire trim or remove the lateral fins produced; further in producing the die parts with means to limit their approach to prevent crushing of the cutting edges.

Our invention also comprehends details of construction which, together with the features above specified, will be better understood by reference to the drawings, in which:

Figure 1 represents an end elevation of a

two part wire drawing die embodying our invention; Fig. 2 represents a similar elevation of a die showing a modified construction; Fig. 3 represents a section on line $x-x$ of Fig. 1; Fig. 4 represents a plan of the face of one of the die parts shown in Fig. 1; Fig. 5 represents a transverse section of the die drawing and cutting parts showing the material within the die and the severed fins at each side thereof; Fig. 6 represents an end elevation of a two part die embodying our invention for drawing an oval shape, and showing another embodiment of the fin cutting means; Fig. 7 represents an end elevation of a two part die embodying our invention for drawing a rectangular shape, and showing another embodiment of the fin cutting means; and Fig. 8 represents a side elevation, partly in section, of a machine for drawing wire through the dies.

The wire drawing die forming the subject matter of the present invention is made in two parts, 1 designating the lower die part and 2 the upper die part, and in the form shown in Fig. 1 each part is identical in construction, as will be readily seen.

3 designates a groove cut in the surface of each die part at substantially the center thereof and extending longitudinally from one side of the part to the other so that when the two parts of the die are superposed in operative relation, the grooves of each will form together a hole of the diameter corresponding to which the wire is to be drawn. By reference to Fig. 3 it will be seen that the longitudinal section of the groove 3 is substantially an arc of a circle so that when the parts of the die are closed the aperture formed by these two grooves will have its side walls converging from each side of the die toward the center, thus forming an entrance opening at the side of the die of the same diameter as or greater than the original wire stock, while the diameter at the center corresponds to the diameter to which the stock is finally drawn. By making the die aperture tapering from each end the die may be reversed if so desired. If it is only to be used for drawing the wire in one direction, then the taper need not be the same at both ends. In the preferred form of the invention the meeting edges 4 of the two parts of the die diverge with respect to each other as shown at 5, whereby a definite cutting edge is formed extending the

length of the groove 3 and serving to shear the material during the initial pinching or coming together of the die parts so that the fin shown at 6 is cleanly severed from the body of the wire.

In the form shown in Fig. 1 each part of the die adjacent the shearing part 5 is provided with a longitudinal recess 7 to receive the fins or chips which are removed from the wire. At the outer side of the recesses 7, and at each side of the die, the material of the parts is suitably surfaced as shown at 8 to form contacting abutments for the two parts of the die in order to limit the closing of the parts and thus prevent the cutting edges 4 from unduly pressing one upon the other and damaging the said cutting edges.

In Fig. 2 we have shown a modified form wherein the lower die part 1 is provided with a flat anvil surface 9 at each side of the groove 3 and also has the longitudinal recesses 10 therein for the reception of chips and the like. The die part 2 is, however, formed similar to one of the die parts shown in Fig. 1, having the cutting edges at 4 and curved faces 5 diverging from the anvil portion and forming a part of the recess 7 as in the die described in Fig. 1. The abutments in this modification are also similar to those described in Fig. 1, and are therefore denoted by the same reference numeral 8.

In Fig. 6 we have shown the die parts 1 and 2 provided with grooves 11 which, when superposed, provide an oval shaped channel, capable of reducing the wire to an oval shape during the drawing operation. In this modification the two parts of the die are preferably duplicates and therefore the description of one part will be understood as applying to the other. Adjacent one side of the groove 11 the part 1 is provided with an anvil surface 12, also preferably with a longitudinal recess 13 to receive the chips and the abutment bearing surface 14, while that portion of the die on the opposite side of the groove 11 is provided with a cutting edge 15 from which the material curves outwardly as shown at 16 into the recess 17. In this construction the cutting edges 15 cut upon the anvil portions 12. At the outer sides of said recesses the die parts are provided with the abutment portions 14, as in the cases previously described.

In Fig. 7 the die parts are provided with a groove 18 shaped to form a rectangular drawing of the wire, and one of the parts is provided with anvil surfaces 19 at each side of the opening, while the opposite part has cutting edges 20 with the surfaces curved away in convex form as shown at 21. The two parts of the die are recessed to form the clearance openings 22 for chips, as already described.

In Fig. 8 we have shown the die parts 1 and 2 mounted within a suitable box 23 on the machine frame 24 and forced together upon the wire through the medium of the screw 25. 26 designates the clamping head of the machine for holding the end of the wire, and the said head is operated, in the present instance, by way of example, by being attached to a feed screw 27 which may be operated by the hand wheel 28, in which it is screwed. In the operation and use of the die forming the subject matter of our invention, it will be noted that the same is more particularly adapted to drawing wire into lengths of different cross sectional area, either in a strand of determined length or in a continuous length of material.

In drawing operations as heretofore carried out, the initial compression or biting of the parts of a die upon the material causes the same to fin or expand laterally, which fin or fins must be chipped or broken off by a separate operation after the completion of, or at least after the initial drawing operation. The result of removing the fins in this manner is not satisfactory for the reason that the material is left with a rough or uneven surface where the fin has been removed, which renders the completed article defective to a degree. This is particularly the case where the drawn wire is used for hair pins as the rough line or edge catches in the hair and interferes with the free operation of the pin. Furthermore, there is considerable uncertainty in the removal of these fins and this necessitates the expense of inspection and loss from imperfections. In our present invention, while such fins are necessarily formed during the initial pinching or biting of the die, the said fins are simultaneously severed from the material by the action of the cutting edges 4 so that when the material is drawn through the die the surface at the beginning of the reduction has a uniform smooth finish, the severed fins or chips dropping into the recesses at the side of the die opening. Furthermore, since the fins are removed by the initial drawing step, the heretofore secondary step of the fin cutting is entirely eliminated and the wire or article drawn from the die is in a substantially finished condition.

While we have in the accompanying drawings shown the abutments as a part of the die, it will of course be understood that we do not wish to be limited to this exact construction, as obviously such abutting surfaces might be otherwise provided to accomplish the same end.

Furthermore, we do not desire to be restricted to the provision of recesses or clearance spaces within the die parts for the reception of chips, and the construction shown is merely the preferred one for the purpose.

Having thus described our invention, what we claim as new and desire to secure by Letters Patent is:—

1. A two-part wire drawing die, provided with abutment surfaces to limit the movement of the die parts toward each other under clamping action, said parts being also respectively provided with a tapered groove forming an opening for drawing the material, and one of said die parts having a cutting edge formed at either side of its groove whereby the fin or fins formed during the initial clamping of the die is severed.

2. A two part wire drawing die, provided with abutment surfaces to limit the movement of the die parts toward each other under clamping action, said parts being also respectively provided with a tapered groove forming an opening for drawing the material, a cutting edge formed on one of said parts at either side of said opening whereby the fin or fins produced during the initial clamping of the die is severed, one of said dies having a clearance space at each side 25 of the drawing opening to receive the severed fin or chips.

3. A two-part wire drawing die having its parts each formed with a tapered groove, said groove opposed to provide a tapered opening and said die also having means arranged in alinement with the sides of the grooves to sever a fin formed between the die parts in the initial clamping operation, and further with abutment portions to limit the approach of the two parts of the die and clearance spaces for the fins on each side of the opening and between the abutment portions and the severing means.

4. In a wire drawing mechanism, the combination of a die formed of two parts relatively movable toward each other and providing a tapered groove with cutting edges at the juncture of the die parts adjacent to the groove, means for drawing a wire strand through the die and between the two portions thereof, and means for closing the two die portions upon the wire strand, and holding them closed during the drawing of the wire strand through the die and between the portions thereof, the said die parts compressing the strand and severing a fin or fins formed on said material during the initial clamping of said die parts.

5. In a device of the character stated, a frame, a clamping member mounted thereon, a two-part wire drawing die adapted to be operatively held by said clamping member, said die being provided with abutment surfaces to limit the movement of the die parts toward each other under the action of said clamping member, said die parts being also respectively provided with a tapered groove forming an opening for drawing the material and one of said die parts having a cutting edge formed at either side of its groove for severing the fin or fins formed during the initial clamping of the die, and means to grip and draw the material through said die.

In testimony of which invention, we hereunto set our hands.

LOUIS C. BELZ.
ARNOLD NACKE.
